CLAIM

We claim the ornamental design for a vacuum cleaner, as shown.

DESCRIPTION

FIG. 1 is a perspective view of a vacuum cleaner showing our new design;

FIG. 2 is a right side view of the vacuum cleaner of FIG. 1.

FIG. 3 is a left side view of the vacuum cleaner of FIG. 1.

FIG. 4 is a front view of the vacuum cleaner of FIG. 1.

FIG. 5 is a back view of the vacuum cleaner of FIG. 1; and,

FIG. 6 is a top view of the vacuum cleaner of FIG. 1.

The elements shown in broken lines indicate environmental structure that forms no part of the claimed design.
